AIR CONDITIONING APPARATUS

Glenn F. Zellhoefer, Bloomington, Ill., assignor
to Williams Oil-O-Matic Heating Corporation,
Bloomington, Ill., a corporation of Illinois

Application January 5, 1933, Serial No. 650,230

3 Claims. (Cl. 257—8)

This invention relates to improvements in air conditioning apparatus and more particularly to an apparatus of this character which may be employed for the circulation of warm air during cold weather and cold air during warm weather.

It is an object of this invention to provide a refrigeration system of the absorption type in which the still is operated by steam from a boiler and by circulating the refrigerant in a bath of water which is caused to circulate through a radiator coil in the air distributing system for cooling the air passing thereover for use in warm weather and upon disconnecting the still and circulation of cold water through the radiator coil in the air circulating system, the steam from the boiler may be passed through said radiator coil and the condensate from the said coil returned to the boiler.

It is readily seen that by the installation of such a system, the operation of the boiler may be continuous, if so desired, and by the manipulation of certain valves in the system, either cool or warm air may be supplied through the air circulation system of the building.

With these and other objects in mind, reference is made to the accompanying sheets of drawings which illustrate a preferred embodiment of this invention, with the understanding that minor detail changes may be made without departing from the scope thereof.

Figure 1 is a view in perspective of an embodiment of this invention.

Figure 2 is an enlarged detached view partly in section and partly in front elevation of a form of heat exchanger for the cooling liquid.

It is preferable to employ an absorption refrigeration plant of the non-intermittent type, such as disclosed in this applicant's co-pending application Serial No. 651,306, filed January 12, 1933, which includes a still S for distilling the refrigerant off the solution or strong liquor by the application of heat produced by steam from the boiler B. This boiler may be of any type which will produce sufficient steam for the purpose specified and may be operated by an oil burner O, as shown, by gas or by coal, as desired.

The steam from the boiler B is conducted by way of pipe 1 and pipes 3 and 4 to the still S and preheater within the still, not shown. The strong liquor or solution of the refrigerant and solvent, preferably those disclosed in this applicant's co-pending application Serial No. 651,306, filed January 12, 1933, by means of a motor operated pump P is conducted from the absorber A by way of pipe 5 to the still. The gaseous refrigerant separated from the solution in the still passes

through the rectifier F and pipe 6 to a conventional condenser C and into a conventional receiver D. The refrigerant is then conducted by pipe 7 through an evaporator E contained in a water bath W or heat exchanger coil and from the evaporator by pipe 8 to the absorber A. The weak or virgin liquid is conducted from the still by pipe 9 to the absorber.

A motor operated fan blower is mounted in a housing H for circulating air through the duct A' connected with the air circulation system of the building. A conventional radiator coil 10 is mounted between the entrance of the duct A' and the fan housing H. The water cooled by the evaporator in the water bath W is circulated by the small pump P', which may be driven by a belt from the shaft of the blower fan as shown, through pipe 11 and pipe 12 to the radiator 10 and by pipes 13 and 13^a returned to the top of the water bath or heat exchanger coil.

For compactness, efficiency and cheapness of construction, it is preferable to use a heat exchange coil, such as shown in Figure 2, consisting of an inner coil E' in which the refrigerant is vaporized and an outer coil 11^b through which the water is circulated and thence circulated through the radiator coil 10 in place of an evaporator coil submerged in a tank of water, preferably by connecting the intake side of a motor driven pump P'', see Figure 2, with the water discharged into the tank W by the return pipe 13 from the coil 10 and the discharge side of the pump P'' to the outer coil 11^b which in turn is connected by the pipe 11 to the intake of pump P'.

When the refrigeration system is in operation, cold water will be circulated through the radiator 10 and the fan blower will force air through the radiator to supply cool air to the air circulating system.

Valves 3^a and 4^a are provided in steam pipe 1 which are adapted to shut off the steam supply from the boiler to the still, and valve 11^a is provided in pipe 11 as it leaves the bottom of the water bath, valve 12^a is provided in pipe 12 as it leaves the pump P', and valve 13^b between pipes 13 and 13^a returning from the coil 10 to the top of the water bath which valves are adapted to be closed to prevent circulation of water through the radiator coil 10. The steam pipe 1 leading from the boiler is connected by pipe 14 to the pipe 12 leading to the radiator 10 and is provided with a valve 14^a as it joins the pipe 12 which valve is adapted to cut off the steam when

the cooled water is circulated through the radiator 10. When this valve 14^a is opened and the other valves are closed, steam will be conducted from the boiler by ways of pipes 1 and 14 to the radiator 10 so that when the fan blower is in operation, it will force air over the heated radiator to supply warm air to the air circulating system of the building. Connected to the discharge side of the pump P' is a pipe 15 leading therefrom to the water side of the boiler B and is provided with a valve 15^a adapted to be closed while the radiator 10 is cooled and to be opened when it is steam heated and a valve 13^c, closed when valve 13^b is open, is provided in the pipe 13^d connecting the pipe 11 to this pipe 10, so that when the fan blower is in operation, the pump P' will circulate the condensate from the coil through the pipe 13 and pipe 11 to the pump and from the pump through pipe 15 to the water side of the boiler.

The details of the construction of the still S, rectifier F, and evaporator A are fully disclosed in applicant's co-pending application Serial No. 651,306, filed January 12, 1933.

From the above it is readily seen that when valves 14^a and 15^a are closed and valves 3^a, 4^a, 11^a, 12^a, and 13^b are opened, and the boiler B in operation, cool air will be furnished the air circulating system and by closing valves 3^a, 4^a, 11^a, 12^a, 13^c and 13^b, and opening valves 14^a and 15^a, warm air will be supplied to the air circulating system.

Water for the cooling coils in the absorber A, condenser C, residual heat coil within the still, and rectifier F is supplied by the pipe 16 from source of water supply to the absorber coil and from thence by pipe 17 to the residual heat coil within the still S, and from thence by pipe 18 to the outside coils of the condenser C from which the water passes by pipe 19 through the rectifier F and from thence by the pipe 20 to the drain.

What I claim is:

1. An air conditioning apparatus for an air circulating system including an air conditioning radiator and a motor driven air circulating

45

fan for forcing air to be conditioned through said radiator into the system, a steam boiler, means for connecting and disconnecting steam therefrom to a steam operated absorption refrigeration plant, a refrigerated fluid tank, refrigerating means within the tank connected to the refrigerating plant, a circulating pump operated in unison with the circulating fan, means for connecting and disconnecting the pump to the fluid tank for circulating the refrigerated fluid through the conditioning radiator, and means connecting and disconnecting the pump to the steam boiler for circulating the steam through the conditioning radiator, and means for returning the condensate to this boiler, whereby the boiler, fan and pump operate continuously to provide cold air to the system when the steam boiler is connected to the refrigeration plant and disconnected to the pump and hot air to the system when the steam boiler is disconnected to the refrigeration plant and connected to the pump.

2. The structure set forth in claim 1 in which the connections of the pump to the radiator and fluid tank are provided with valves to control the flow of refrigerated fluid steam and condensate through the same connections of the pump.

3. In an air circulating system the combination of a continuously operating boiler, a continuously operating fan and a continuously operating pump for conditioning the air in said system, with an air conditioning radiator through which the fan forces air into the system, a refrigerated fluid tank, a steam operated absorption refrigeration plant adapted to be connected to the refrigerating element of the refrigerating plant to refrigerate the fluid in said tank, means adapted to connect the fluid tank to the pump and radiator to circulate this refrigerated fluid through the radiator and means adapted to connect the boiler to the pump to circulate the steam through the radiator and return the condensate to the boiler as may be desired.

GLENN F. ZELLHOFER.
